DISPLAY STAND

Charles A. Follett, Canajoharie, N. Y., assignor to
Beech-Nut Packing Company, Canajoharie,
N. Y., a corporation of New York

Application July 10, 1936, Serial No. 89,962

3 Claims. (Cl. 211—49)

The present invention relates to display stands and comprises a device of this type which is of simple and strong construction, of pleasing appearance, and convenient in use. The improved stand is particularly adapted for displaying small rectangular boxes of the type commonly used for candy coated chewing gum, cough drops and the like and is so constructed as to display such packages prominently and attractively and in such position as to be readily accessible for removal by a customer.

The various features of novelty, and the advantages adherent thereto will be apparent from the following description and from the drawing to which reference may now be had.

Figure 1 is a front view of a display stand illustrating the preferred embodiment of the invention.

Fig. 2 is a vertical sectional view along the line 2—2 of Fig. 1;

Fig. 3 is a horizontal sectional view along the line 3—3 of Fig. 1;

Fig. 4 is an enlarged vertical sectional view along the line 4—4 of Fig. 3; and

Fig. 5 is an enlarged sectional view of the lower portion of the stand.

In the embodiment of the invention illustrated in the drawing, the new display stand comprises a casing having a bottom wall 2, a drawer 4 movable upon the base 2, side walls 6 secured to the base and forwardly inclined shelves 8 positioned above the drawer 4 and carried by the side walls 6. The drawer 4 may be conveniently formed from a single rectangular sheet of metal the edges of which are turned upwardly to form side walls 5, a relatively higher rear wall 7 and a shallow lip or flange 9 at the front. The side walls 5 are turned inwardly at their forward end as indicated at 11 (Fig. 3).

A ring or handle 13 is secured to the rear wall 7 of the drawer. The drawer is divided into three compartments 10 by means of double walled metal partitions 12 riveted to the base of the drawer. Within each compartment 10 is a follower comprising an upright plate member 14 having a vertical wall portion and a rearwardly and upwardly extending portion 15, and a coiled compression spring 16; the vertical portion of the plate and the forward turn of the spring being held together by tongues 17 pressed from the metal of the plate. The rear turn of the spring is secured to the rear wall 7 of the drawer. A rail or article supporting runway 20 is provided in each compartment 10 as a guide for the spring 16 and plate 14, each plate member being cut away at its lower center

to embrace the rail and the lower reaches of each turn of the spring 16 passing beneath the rail.

Positioned in each compartment in advance of the follower 14 are the boxes 22 to be displayed. The boxes are arranged in upright position one behind the other; the follower engaging the flat surface of the last box and urging the stack forwardly. The forward end of each rail 20 slants abruptly upward to cause the most forward article in each compartment to extend above the succeeding articles making it easier to grasp for removal. When a package is removed at the front of the compartment, the plate 14 urged forwardly by the spring 16 advances the entire stack 15 of articles along the rail 20; the front article being moved upwardly by the rail and forwardly by the follower into position of ready accessibility.

Each partition 12 carries at its forward end a relatively narrow plate 24 which extends over 20 the edges of the forward box 22 sufficiently to engage the front wall thereof without concealing the box from view. The small flanges 11 on the sides of the drawer serve, together with the plates 24, as forward stops for the boxes in each compartment whereby the boxes maintain their vertical stacked position when the drawer is removed for restacking. When the drawer is in its normal position, the foremost boxes in the compartments are visible through the opening in the front of the casing and appear attractively framed by the plates 24, and by a metal strip 23 extending across the lower front of the casing and secured to the base 2.

Integral with the bottom wall 2 are vertical 35 wall sections 25 (Fig. 4) which extend along the side walls 6 for a distance corresponding to the height of the sides 5 of the drawer. The upper edge of each section 25 is turned over to form a guide channel for the side wall of the drawer. 40 Suitable buttons 26 of rubber or the like riveted to the base 2 serve as feet for the display stand. The bottom and side walls are riveted together and are also held in fixed relation by a rod 28 which extends horizontally through a bead 29 45 formed in the rear edge of the bottom wall and vertically through a similar bead provided along the rear edge of each side plate.

The inclined shelves 8, which are provided for the display of additional articles, are so positioned that articles may be easily removed from the front of the drawer 4 without interference with the lower of the shelves and articles from the lower shelf may be removed without interference with the upper shelf. Articles, such as 50 55

packages 32 of chewing gum, which are delivered to the lower shelf 8 from the rear, feed forward by gravity until they abut against a flange 33 at the forward edge of the shelf. Preferably the 5 width of the shelves 8 is about equal to twice the length of a package of chewing gum of standard size and the width of each compartment 10 is such that a standard size package of candy coated gum may be stood on end therein.

10 In stocking or replenishing the stand, the drawer 4 is pulled out at the back by the ring 13, the portions 15 of the follower 14 grasped and the follower moved back to compress the spring 16. The articles are then inserted into the compartment 15 in advance of the follower. As few or as many articles may be used as desired, as the appearance of the stand from the front, so long as a single article remains in each compartment, will be substantially the same irrespective of the 20 number of articles in each compartment. Due to the manner in which the followers 14 are mounted for movement along the guides 20, the springs 16, when the followers are moved rearwardly, will not buckle but will compress uniformly and, upon release of the followers will expand and urge the followers forward into firm contact with the stack of boxes.

As the foremost article is removed, the next 30 succeeding article in the compartment is moved forwardly and projected upwardly into position to be displayed to the best advantage and to enable it to be easily removed.

The substantially open front of the casing and drawer together with the means therein to engage 35 the front edges of the boxes permits of the display of a relatively large area of the front boxes, adding to the attractive appearance of the stand and to the utility of the device for display purposes. The rearwardly removable drawer with 40 its self-contained means for holding and feeding forward the packages therein adds to the utility of the device in providing access from the rear for restocking without disarrangement of the display. The stand may be cheaply made of 45 sheet metal, is of simple and strong construction, and the manner in which the articles are advanced into an easily accessible position adds materially to the attractiveness of the display as well as the convenience of the device.

50 The following is claimed:

1. A display stand of the class described comprising a casing having an opening in the front

thereof, a support within the casing upon which a plurality of articles arranged in stacked relation one behind the other are adapted to slide toward said opening, the forward end of said support being inclined upwardly and forwardly 5 so as to cause the upper end of the foremost article to project a distance above the others, an abutment for the foremost article adjacent the forward end of said support adapted to be engaged by the front side of the foremost article, and spring-actuated means for yieldingly engaging the rearmost article for pressing the stack of articles against said abutment whereby the foremost article is prominently displayed and may be conveniently removed through said opening 10 in the casing and upon removal the remaining articles in the stack are advanced and the next succeeding article is projected upwardly to take the place of the article removed.

2. In a display stand for articles of the class 20 described, the combination comprising a casing having an opening in the front thereof, a drawer mounted to slide in said casing toward and from said opening and removable from the rear of the casing, partitions in said drawer dividing the 25 same from front to back into a plurality of compartments, a runway in each compartment of said drawer, and feeding means in each drawer for urging articles forwardly on said runway, said runway being inclined upwardly at its forward 30 extremity whereby, when an article is removed from the forward end of said drawer through the opening in the front of the casing, said feeding means urges another article both forwardly and upwardly into accessible position.

3. In a display stand for articles of the class 35 described, a casing having an opening in the front thereof, a drawer mounted to slide in the casing toward and from said opening having a compartment therein extending longitudinally thereof, a runway in said compartment extending longitudinally thereof for supporting articles one behind the other in stacked relation, a follower mounted to slide in the compartment and engaging the rearmost article, and a coiled spring 40 interposed between the follower and the rear end of the compartment for pressing the follower forwardly, said spring having its forward end secured to the follower with the lower portions of the coils of the spring passing beneath the 45 runway so as to be guided by the runway.

CHARLES A. FOLLETT.
